H. D. CLINTON

TWISTER SPOOL SLOT PROTECTOR

Filed March 15, 1926

UNITED STATES PATENT OFFICE.

HARRY D. CLINTON, OF JOHNSON CITY, NEW YORK.

TWISTER-SPOOL SLOT PROTECTOR.

Application filed March 15, 1926. Serial No. 94,924.

This invention relates to driving connections between driving spindles and twister spools, and more particularly to means for protecting the slotted ends of spools having wooden barrels and vulcanized fibre heads.

- A common form of protector of the character referred to, heretofore employed, consists of a metal plate having an oblong slot 10 therein co-incident with the oblong slot in the end of the spool and secured to the spool head by means of screws which are liable to work loose and cause trouble, usually resulting in rendering the spool unfit for 15 use after the protector plate has worked loose, rendering it necessary to tighten the screws at intervals in order to prevent trouble, and such devices are also rather expensive. Furthermore, such protectors are not suitable 20 for use on hard fibre head spools in which the end of the wooden barrel to be connected with the driving spindle is extended beyond the hard fibre head, as in the case of my improvement.
- 25 A metal plate with end portions shaped to conform to the shape of the ends of the slot in the spool head and with its intermediate portion embedded in the spool head so as to embrace the slotted end of the 30 wooden barrel, and forming a lining for the ends of the slot to prevent wear, has also been employed, but such construction leaves the intermediate portion of the slot, or that portion which is formed in the end of the 35 barrel, exposed to wear, and such devices are unsatisfactory and are also unsuitable for use with a spool having a wooden barrel with the end thereof extended beyond the fibre head.
- 40 My invention has for its object to provide a simple, efficient and inexpensive protector for the projecting end of the wooden barrel of a twister spool having vulcanized fibre heads, and which will not be subject to the 45 foregoing objections, and will thoroughly protect and prevent wear and injury to the slotted end of the wooden barrel of a vulcanized fibre head twister spool.

50 Other objects are to provide a protector or shield for the projecting end of the wooden barrel of a vulcanized fibre head spool, which is inexpensive to make and may be easily applied and immovably secured on the projecting end of the barrel in such manner as to lock the protector in place

without using other fastening means than such as are inherent in the protector itself and the barrel end co-operating therewith.

The invention will first be hereinafter more particularly described, with reference 60 to the accompanying drawings, which are to be taken as a part of this specification, and then pointed out in the claims at the end of the description.

In said drawings, Fig. 1 is a side elevation 65 of a twister spool having a driving connection with a driving spindle and having a protector for the spool end embodying my invention;

Fig. 2 is a vertical sectional elevation of 70 the twister spool and driving spindle, partly broken away and showing the driving connection;

Fig. 3 is an end view of a twister spool 75 having a wooden barrel with a slotted end projecting through a vulcanized fibre head and having my improved protecting device applied thereto; and

Fig. 4 is a detail perspective view showing 80 the slotted end of the wooden barrel of a twister spool and a protecting device embodying my invention in position for assembling and securing the two parts together.

Referring to said drawings, in which the 85 same reference letters are used to denote corresponding parts in different views, the twister spool shown has a wooden barrel A with a central bore and vulcanized fibre heads B, and the barrel has a reduced extension A¹ at one end which projects through a central opening in the fibre head and is formed or provided with a transverse slot or recess a spanning said central bore and slightly concave on opposite sides to make the center of the slot or recess of the same 90 size and shape as said central bore and form in effect a continuation thereof to adapt the spool to be mounted on a driving spindle C. The projecting end A¹ of the barrel is exteriorly grooved to provide an exterior marginal protuberance or rib a² on each side of the slot. At its junction with the end of the spool or wooden barrel the spindle has an enlarged base portion C¹, which is formed or 95 provided on the upper end thereof with angular lugs or projections c on opposite sides adapted to fit within the slot or recess a in the projecting end of the spool or wooden barrel A, and form a driving connection with the spool. For rotating the spindle it has a 100 105 110

sheave or pulley C² thereon for connection with a belt driven from any suitable source of power. Said base portion C¹ of the spindle is formed or provided with a shank or 5 reduced extension C³ adapted to fit in a socket on a suitable supporting base so as to permit the spindle to rotate. In order to protect the slotted end of the spool or wooden barrel from wear, with consequent injury 10 thereto when operatively connected with the rotating driving spindle, and also to prevent it from splitting, I provide a protecting device D which may be struck up from sheet metal so as to form a circular body having 15 a transverse centrally disposed depressed portion d, to form a tongue of approximately the same size and shape as the slot in the spool end and adapted to fit snugly within said slot and 20 provide a lining therefor, said device also having laterally extending side portions d¹ of substantially semi-circular form, with the rim or outer edge d² thereof turned so as to overlie and embrace the correspondingly-shaped end portions of the spool or projecting 25 end A¹ of the barrel on opposite sides of the slot therein.

In applying the protector it is placed over the projecting bifurcated end of the spool or 30 wooden barrel and the centrally depressed portion thereof or tongue d is pressed into the slot in the spool end while the rim or marginal portions d² are brought into position to overlie the marginal ribs or protuberances on the spool end, and thereupon sufficient pressure is applied to 35 said marginal portions to force them inwardly toward and against the outer sides of the spool end, thus firmly securing the two parts together in a very efficient and economical manner and without the use of screws or other fastening means than such as are inherent in the protector itself in co-operation with the slotted and externally ribbed spool end, and when once 40 secured in place the protector is not liable to become loose and it cannot be withdrawn from engagement with the spool end by any strain thereon to which it is usually subjected in practical use, as a result of its connection with the driving spindle.

The protector may be formed of sheet metal or other suitable material and it is 45 adapted to serve not only to protect the projecting end of the spool against wear exteriorly, but also to prevent wear upon the side walls of the slot, and it also affords a means for easily engaging the twister spool with a projection or projections on the adjacent end of a driving spindle and the cost 50 of manufacture is reduced to a minimum. It is also much lighter than metal protectors of the kind hereinbefore mentioned, and the expense of applying the same to the wooden 55 barrel end is infinitesimal as compared with

the cost of applying metal protectors of the kind heretofore used for a similar purpose, since it is merely shoved into place over the extended end of the spool or barrel and held in a press with special dies for compressing 70 the side portions of the protector against the outer side portions of the projecting end of the spool or wooden barrel, and thereby securing the protector to the spool so that it cannot be removed without considerable 75 applied force and is not liable to accidental displacement in ordinary use.

Having thus described my invention, what I claim as new and desire to secure by Letters Patent of the United States is: 80

1. In combination with a twister spool having a wooden barrel with one end projecting through a hard or vulcanized fibre head; said projecting end having a centrally disposed transverse slot therein and an exterior protuberance or enlarged terminal 85 extending on both sides of said slot; a metal cap or cover for said projecting end having a centrally depressed portion shaped to conform to the shape of and fit snugly in said slot and laterally extending substantially semi-circular portions overlying said projecting end and having the margins thereof overlying said protuberance and compressed 90 thereagainst and against the spool end so as to firmly secure the two parts together.

2. In combination, a twister spool having a transverse slot in the end thereof and external marginal ribs or protuberances on 100 opposite sides of the slot, and a protecting and strengthening device for the end of the spool and slot comprising a substantially circular metal body having a centrally disposed depressed portion extending transversely thereof of a width sufficient to receive an oblong projection or tongue on a driving spindle and shaped to conform 105 to the shape of and fit snugly within and fill said slot; said device also having substantially semi-circular laterally projecting side portions which overlie said ribs and end portions of the spool end and have their free ends compressed against the sides of the spool end so as to firmly secure the two 110 parts together.

3. A twister spool having a wooden barrel with one end projecting through a hard or vulcanized fibre head, said projecting end having external ribs thereon and a transverse slot therein, and means for protecting 115 and strengthening said barrel end; said means consisting of a sheet metal body of substantially circular form having a centrally depressed portion of sufficient width to receive a rectangular projection or tongue on a driving spindle and shaped to conform 120 to the shape of and fit snugly within said slot and provide a metal lining therefor; said body also having laterally extending substantially semi-circular portions overly- 125 130

- ing said ribs and correspondingly-shaped parts of the spool end and secured thereto by compressing the rim or margin of the protector against the spool end.
5. In a device of the character described, a wooden barrel having an end projecting through an inflexible head; said end having a transverse slot therein and external protuberances thereon on opposite sides of the slot, and a device for protecting and strengthening said slotted end comprising a metal cap having a centrally disposed depressed portion of sufficient width to receive a rectangular end-portion of a driving spindle and shaped to conform to the shape of and fill said slot and also having integral substantially semi-circular laterally projecting portions or wings overlying said protuberances and projecting end of the barrel and pressed thereagainst so as to firmly secure the cap thereto and provide a metal lining co-extensive with said slot.
4. A protector for a twister spool slot in the end of a wooden barrel projecting through a head of hard fibre or the like, comprising a metal body of circular form having a centrally depressed portion shaped to conform to the shape of the slot in the spool end and of sufficient width to receive therein an oblong projection on the end of a driving spindle; said spool end having external ribs on opposite sides of the slot therein and said protector having integral laterally extending substantially semi-circular side portions overlying said ribs and correspondingly-shaped parts of the spool end and secured thereto by compressing the margins of said side portions of the protector against the end of the spool.

In testimony whereof I affix my signature.
HARRY D. CLINTON.
